UNITED STATES PATENT OFFICE.

GRANT HOLMES, OF DANVILLE, ILLINOIS, ASSIGNOR TO ROBERT HOLMES & BROTHERS, OF DANVILLE, ILLINOIS, A CORPORATION OF ILLINOIS.

END-LOADING CHUTE.

No. 893,626.

Specification of Letters Patent.

Patented July 21, 1908.

Application filed September 9, 1907. Serial No. 391,915.

To all whom it may concern:

Be it known that I, GRANT HOLMES, a citizen of the United States, residing at Danville, in the county of Vermilion and State of Illinois, have invented certain new and useful Improvements in End-Loading Chutes, of which the following is a specification, reference being had therein to the accompanying drawings.

10 This invention relates to end loading chutes for loading coal cars, and the object of the invention is to provide a chute of this character which may be supported above a coal car in such a manner as to load the coal 15 into the car as the car is moved beneath the same; which may be moved out of the way to permit the passage of box cars or cars of larger size than the coal car; to so construct the chute that it will properly distribute the 20 coal within the car and will build up a load that will ride well; and further, to so construct the same that it may be adjusted to regulate the distribution of coal within the car.

25 With these objects in view my invention consists in certain novel features of construction and in certain parts and combinations hereinafter to be described, and then more particularly pointed out in the claims.

30 In the accompanying drawings, Figure 1 is a side elevation of a loading apparatus embodying my invention; Fig. 2 is an end elevation of the same; Fig. 3 is a side elevation of the loading chute; Fig. 4 is a rear 35 end elevation of the same; and Fig. 5 is a top plan view thereof.

In these drawings, I have illustrated the preferred form of my invention and have shown the same as comprising a frame 1 extending above a railway track and of dimensions sufficient to afford ample clearance for the cars. Pivotally supported from the frame 1 and above the track is a loading chute 2 which may be of any suitable construction, but I prefer that herein shown which comprises a frame consisting of substantially vertical side members 3 connected at their front and rear ends by transverse bars 4 and 5, respectively, the rear bar 5 being of less length than the forward bar, thereby causing the vertical side members 3 to converge toward the rear. This frame is provided with a suitable bottom which is

preferably inclined downwardly and forwardly relatively thereto, and, in the preferred form which is here shown, consists of a flat substantially triangular member 6 having its base secured near the lower edge of the rear transverse member 5 of the frame and extending downwardly and forwardly 60 therefrom. Other substantially triangular members 7 are arranged on opposite sides of the flat triangular member 6 and have their apices secured near the base of said flat triangular member and are connected at one 65 edge to the adjacent edge thereof, thence extend upwardly in a curved line and have their opposite edges secured to the vertical side members 3, preferably by means of suitable bolts 8. This construction provides a 70 downwardly and forwardly inclined bottom for the chute having its central portion flat and its side portions curved which produces a chute, the rear end of which is substantially rectangular in cross section, while the 75 forward end thereof is substantially semi-circular in cross section.

The members 6 and 7 are preferably of a length substantially equal to the length of the side members 3, and, owing to their 80 downward inclination, the front edges of these members, that is the apex of the central member and the bases of the two side members, are located in the rear of the front transverse member 4 of the frame and form a 85 gradually receding discharge mouth for the chute. This discharge mouth is preferably provided with a series of forwardly extending fingers 9, which are secured near the front edge of the downwardly inclined bottom 90 and extend in substantial alinement therewith. These fingers may be of any desired construction, but I prefer that the same should be T-shaped in cross section, as here shown, as this provides a maximum strength 95 with a minimum weight. These fingers also preferably diverge slightly towards their outer ends, thus serving to separate the coal according to the size of the lumps by permitting the small coal to pass between the same 100 close to the chute and drop to the bottom of the car, while the larger coal is carried further from the chute before it can pass between the fingers, and the very large lumps pass off the ends of the fingers, thereby causing this 105 larger coal to fall upon the small coal which

has already passed between the fingers, and as the car moves slowly forward causing the small coal to be loaded in the bottom of the car and the larger lumps on top thereof, thus 5 packing the load to the best advantage and building up a load which will ride well.

The upper edges of the bottom of the chute are preferably adjustably secured to the side members 3 of the frame in order to 10 permit the downwardly inclined bottom to be adjusted to regulate the distribution of the coal within the car. This adjustment may be secured in any suitable manner and I have here shown the side members 3 as provided with two or more series of apertures 10, 15 each series being arranged radially to a central aperture 11 and adapted to register with the apertures in the upper edges of the bottom portion, thus permitting the angle of inclination of the bottom portion relatively to the frame or side members 3 to be varied by removing the bolts 8 and inserting them in a different series of apertures. One of the side members 3 is preferably cut away at its 20 upper edge, as shown at 12, to receive the discharge end of a feed chute 13, extending from the coal delivery screen 14 to the loading chute 2. An outwardly extending flange or lip 15 is secured to the side member 3 beneath said cut-away portion and the rear transverse member 5 is provided with an outwardly extending portion 16 adapted to engage the rear edge of said flange and support the same.

35 The loading chute 2 may be supported above the coal car in any suitable manner, but I prefer to support the same by means of arms 17 which are pivotally secured at their upper ends to the transverse members of the 40 frame 1, as shown at 18, and are connected at their lower ends to the transverse members of the frame of the loading chute, as shown at 19, preferably near the center of said members. Suitable diagonal braces 20 extend 45 between said arms to strengthen the same and hold them in their proper relative positions. Suitable means are provided for holding the loading chute 2 in its proper position and preventing the same from tipping 50 under the weight of the feeding chute 13. This means preferably consists of arms 21, connected at one end to the frame of the loading chute and adjustably connected at their other ends to the arms 17. Suitable 55 cables or chains 22 are connected at one end to the frame of the loading chute and extend upward and over suitable guides or pulleys 23 mounted on the frame 1, and thence downwardly to a point near the ground where 60 they pass about a suitable shaft 24 provided with a crank 25, whereby the loading chute 2 may be swung upwardly about the pivotal center 18 of the arms 17 and into the position shown in dotted lines in Fig. 2, in which position it is out of the path of any cars, of what-

ever size, that may pass over the railway track. The chute is held in this position by means of a suitable pawl 26 adapted to engage a ratchet 27 on the shaft 24. The cables 22 may also, if desired, be provided with suitable counterweights 28 to facilitate the lifting of the loading chute. The feeding chute 13, which conveys the coal from the screen to the loading chute, is pivotally connected near the end of the screen and has secured thereto one end of a cable 29 which passes upwardly over guides or pulleys 30 on the frame 1 and thence downwardly to a point near the ground, where it is connected to a suitable shaft 31 provided with a pawl 32 and ratchet wheel 33, whereby the feeding chute may be moved upwardly and out of the path of the car. An auxiliary feeding chute 34 is also provided and is movably mounted beneath the ends of the screen 14 85 by means of links 35, which permit the same to be moved outwardly so that the outer end thereof will project through the side door of a box car to permit coal to be loaded into the same.

The operation of the device will be apparent from the foregoing description, and it will be seen that I have provided a loading apparatus of the character described, in which the loading chute can be adjusted above the coal car and near the top thereof to feed the coal into said car while the same is moved beneath the loading chute and can be quickly swung up out of the path of other cars which may be moved over the tracks; that the loading chute is so constructed as to properly distribute the coal within the car, loading the small coal in the bottom and the lumps on top and rounding the load on top, thereby packing the load to the best advantage and 100 building a load that will ride well; and, further, that the loading chute may be adjusted to regulate the distribution of coal in the car.

I wish it to be understood that I do not desire to be limited to the exact details of construction shown and described, for obvious modifications will occur to a person skilled in the art.

Having thus fully described my invention, what I claim as new and desire to secure by 115 Letters Patent, is:—

1. A loading chute of the character described comprising a substantially horizontal upper portion, a downwardly inclined bottom, and forwardly extending screening fingers carried by said bottom and diverging towards their outer ends.

2. A loading chute of the character described comprising substantially vertical side members, a downwardly inclined bottom connected at its edges to said side members, said bottom having curved side portions and a flat portion between said curved portions, and forwardly extending fingers carried by said bottom.

3. A loading chute of the character described comprising a substantially horizontal upper portion, a downwardly inclined bottom, said bottom having curved side portions, and a flat portion extending between said curved portions for substantially the full length of said bottom.

4. A loading chute of the character described comprising substantially vertical side members, a downwardly inclined bottom connected at its edges to said side members, said bottom having a flat triangular central portion, and a curved side portion.

5. A loading chute of the character described comprising a frame having substantially vertical side members, a flat triangular member having its base secured to the rear wall of said frame and extending downwardly and forwardly therefrom, other substantially triangular members having their apices secured near the base of said flat triangular member and extending in curved lines from the edges of said flat member to the adjacent edges of said side members.

6. A loading chute of the character described comprising a frame having substantially vertical rearwardly converging side members, a downwardly and forwardly inclined bottom secured at its edges to said side members, and forwardly extending fingers secured to said bottom.

7. A loading chute of the character described comprising a frame having substantially vertical side members, a downwardly

and forwardly extending bottom adjustably secured at its edges to said vertical side members, and fingers carried by said bottom.

8. A device for loading coal cars comprising a frame adapted to extend on the opposite sides of the car, arms pivotally secured at one end to a fixed part of said frame at a point above the plane of said car, an end-loading chute mounted between the free ends of said arms, means for feeding coal to said chute, and means for moving said arms about their pivotal centers to vertically adjust said chute.

9. A device for loading coal cars comprising a frame having a transverse member extending above the car, arms pivotally connected to said transverse member near one end thereof and having their free ends extending above the car, an end loading chute carried by the free ends of said arms, guides carried by said frame near the end of said transverse member opposite that to which said arms are pivoted, a cable connected to said chute and extending over said guides, and means for actuating said cable to move said arms about their pivotal centers and vertically adjust said chute.

In testimony whereof, I affix my signature in presence of two witnesses.

GRANT HOLMES.
